UNITED STATES PATENT OFFICE

LOUIS JAENICHEN, OF SPRINGFIELD TOWNSHIP, OAKLAND COUNTY, MICHIGAN, AS
SIGNOR TO THE STANDARD COMPUTING SCALE COMPANY, OF DETROIT, MICHIGAN,
A CORPORATION OF MICHIGAN

LEVER FOR SCALES AND METHOD FOR MAKING THE SAME

Application filed November 18, 1926. Serial No. 149,092.

The present invention relates to levers for scales and other weighing devices and to methods of making same.

Among the objects of the invention is to greatly reduce the cost of making such levers and at the same time produce levers having a high degree of accuracy.

In producing levers for scales or other instruments having several knife edge pivots fixed thereto along the lever the securing of the proper alignment of the knife edges is a difficult and tedious operation as ordinarily practiced and therefore expensive.

Another object of the invention therefore is to greatly simplify the aligning operation and enable it to be done quickly and with precision.

Still another object is a lever which can be easily and quickly readjusted to compensate for any wear on the knife edges or bearings therefor.

Other objects will readily occur to those skilled in the art upon reference to the following description and drawings in which:—

Fig. 1 is a plan view of a lever made in accordance with the invention;

Fig. 2 is a side elevation of the same;

Fig. 3 is a perspective view of the lever;

Fig. 4 is a side elevation of a portion of a lever showing a modification.

In making a lever in accordance with the present invention, the lever is first formed by casting or otherwise and machined to finish with the exception of adding the pivots.

Pivots are made somewhat deeper than the usual form, that is, deeper from the knife edge to the bottom opposite said edge and with parallel side faces. There are also prepared a number of slugs of rectangular cross section having the same width and depth as the pivots have.

In forming the lever it is so shaped that it is deeper in those portions in which the pivot's knife edge is pointed downward than in those in which the pivot edge points upward and is preferably provided with bottom surfaces forming an accurate plane.

The lever so formed is placed in a suitable machine and grooves or slots cut across its surface at those cross lines where it is re-

quired to provide the lever with pivots. These slots are cut parallel with each other at right angles to the longitudinal axis of the lever and of such depth that their bottoms are in the same plane. In the preferred form, Fig. 2, the slots are just the depth of the rectangular pivots and slugs in the shallow portions of the lever and twice this depth in the deeper portions.

When the lever has been thus prepared and slotted, the pivots are set in the shallow grooves with their edges up. In the deeper grooves the rectangular slugs are placed in the bottom of the grooves and the pivots then set in the slots with the edges resting on the slugs. This brings the pivot edges all accurately on the same plane as will be readily seen.

After the pivots have been set in the slots as described they may be secured by suitable clamping plates (not shown).

The above method provides a quick, easy and accurate way of producing levers and also provides a lever in which the knife edge pivots may be readily replaced, if necessary, without difficulty.

In the drawings, Fig. 3, a lever is shown at 10 having one end 11 and an intermediate portion 12 somewhat deeper than the rest. These portions, 11 and 12, are provided for the pivots whose knife edges are required to point downward. The portion 13 and end 14 are provided for pivots whose knife edges point upward. The grooves are indicated at 15, the spacing lugs at 16 and the pivots at 17.

The form of lever just described is the preferred form but a modified form is shown in Fig. 4. In the latter the grooves are not all cut to the same depth plane but are cut to just sufficient depth to accommodate the pivots. The pivots are preferably all of the same depth and the cutters are set so that the pivots with knife edges downward will be above the pivots with knife edges upward a distance equal to the depth of a pivot and so on, the higher cutters cutting grooves for those pivots whose knife edges point downward.

In Fig. 4, the various parts are numbered as in the other figures, except that the grooves are indicated at 15^a.

The form first described presents some advantages over the modification as in the former the hardened knife edges rest on hardened slugs, and therefore will not cut in and become loose. Further, it is of advantage to 5 be enabled to use a single size of cutter and align several on a single shaft.

Having now described the invention and the preferred form of embodiment thereof, it is to be understood that the said invention 10 is not to be limited to the specific details herein set forth but only by the scope of the claims which follow.

I claim:—

15 1. A lever of non-uniform thickness adapted to be provided with pivots in the form of knife edged bars, said lever being provided with a plurality of cross grooves cut to the same depth level, the grooves in the thinner portions of the lever being of a depth equal to the vertical dimension of a knife edged bar, the grooves in the thicker portions of the lever being twice this depth.

20 2. A scale lever having a plurality of pivots in alignment, said pivots consisting of knife edged bars set in grooves across said lever, those pivots which point down being spaced from the bottoms of their respective grooves by means of spacing blocks having the same vertical dimension as the knife edged bars and all of said grooves being cut to the same depth level.

25 3. A lever of non-uniform thickness adapted to be provided with pivots in the form of knife edged bars, said lever being provided in one side only with a plurality of cross grooves cut to the same depth level, the grooves in the thinner portions of the lever being of a depth level equal to the vertical dimension of a knife edged bar, the grooves in the thicker portions of the lever being deeper.

40 4. A scale lever having a plurality of pivots in parallel alignment, all of said pivots consisting of knife edged bars set in grooves across one side of said lever, those pivots with knife edges down being spaced from the bottoms of their respective grooves by means of spacing blocks.

50 LOUIS JAENICHEN.
